UNITED STATES PATENT OFFICE.

EUGEN DOLENSKÝ, OF FRANKFORT-ON-THE-MAIN, GERMANY.

PROCESS FOR PRODUCING GAS OF BITUMINOUS FUEL MIXED BY THE GAS OF THE DISTILLATION OF COAL.

1,384,453.

Specification of Letters Patent. Patented July 12, 1921.

Application filed May 31, 1916. Serial No. 100,979.

To all whom it may concern:

Be it known that I, EUGEN DOLENSKÝ, a citizen of Austrian Empire, residing at Frankfort-on-the-Main, in the county of 5 Hesse-Nassau and State of Prussia, Germany, have invented certain new and useful Improvements in Processes for Producing Gas of Bituminous Fuel Mixed by the Gas of the Distillation of Coal, of which the 10 following is a specification.

My invention relates to improvements in the process of producing gas of bituminous fuel by mixing gas obtained by the treatment of distilled fuel with gas resulting 15 from the distillation of coal and in an apparatus adapted to carry out such process.

An object of the invention is to introduce 20 into the upper layer of fuel as hot as possible the gases produced in the coked layer of fuel by the addition of steam.

In previous processes and apparatus, during 25 the blast, the air has been introduced at the lower end of the fuel column so that the hottest point was produced at the foot 30 of the coke layer, hence in the gasification period, the gases entered the coal layer partially cooled and effected only an incomplete 35 gasification.

In the present process, the hottest part 35 of the combustion column lies on the border line between the layer of coke and the layer of green coal. For this reason, according to 40 the present invention, the requisite combustion air is blown in, during the hot blast period, not underneath or above, but approximately 45 at the boundary between the already coked fuel and the still present green coal, and the combustion products are drawn off at the lower end of the fuel 50 column.

In the gasification period which follows, 55 steam is then forced throughout the entire column of fuel. By this process, during the blast, the hottest zone is no longer formed at the undermost or at the upper end of the fuel column, but quite close to the boundary between the already coked fuel and the coal still present. The steam blown in at the lower end of the fuel column during the blast period then produces in the already coked fuel, water-gas which attains its maximum temperature at the aforesaid dividing zone and passes immediately at this maximum temperature into the coal to be coked. By this means, there is obtained

in this part of the fuel column the most favorable action of gasification and distillation. And this advantage is the greater inasmuch as this uncoked fuel column has not yet been deprived of its valuable components, such as tar, benzol and such, by the passage of the combustion products. Moreover, the steam after passing through the coked fuel column, is further passed through the uncoked column in the generator apparatus, through which immediately previously the passage of the hot combustion products took place. It is further pointed out that the steam on its entrance into the generator, does not immediately 60 reach the hottest zone. 65

With generators of this kind the efficient heating of the coke column is realized, by having the lower portion of the shaft occupied by the coke-column subdivided by 70 a fire-bridge of any suitable height whose crown does not reach the zone separating the columns of coke and coal whereby it is possible to blow the coke-column alternately hot from both sides, from below, 75 upward, and then again from above, downward, and vice versa respectively, without the necessity of providing difficult and troublesome air inlets and ports in the middle of the shaft for leading off the burnt 80 gases, but in case of necessity, there may be provided in the neighborhood of the zone separating the columns of coal and coke, further air inlets for the purpose of producing at this place the hottest mass of 85 coke and of obtaining, by the outlets and inlets distributed over the whole section as rendered necessary by the planes or slopes of the grate, a far better uniformity of heating. 90

Also the beginning of the heating of the generator is rendered very easy, as the coke column may be brought at will to red heat, without the necessity of inserting an auxiliary chimney. And even in those cases, 100 where during the gassing operation at the zone separating the coke-column from the coal column, air is in the known manner blown into the passing steam, this form of construction of the shaft may be advantageously made use of. 105

Furthermore, by using such a generator the important technical effects can be attained that the bottoms of the generator are heated to the necessary temperature by the 110

alternate blowing from below upward and then from above downward, and vice versa and the slag is easily removed inasmuch as by the reversed current of air it is drawn to the place where the air enters, at the ash-hole.

The accompanying drawing illustrates the construction of the invention as follows:—

Figure 1 shows a vertical sectional view 10 of the generator furnace according to the lines A—B of Fig. 2.

Fig. 2 shows one side of the same.

In the drawing, α_1 and α_2 are valves for the introduction of the hot-blast air, b_1 and 15 b_2 are valves for the outlets of the combustion products, c_1 and c_2 are valves of the steam duct. d is a chimney in connection with the valve b_2 , there being a similar chimney connected to valve b for the combustion products. e is an air valve, which air can enter through the duct i connected with the steam valve n . f is the escape-pipe for the produced gas and is connected with the receiver h and the valve g . k is the 20 fire-bridge which divides the lower part of the generator and reaches up to near the lower end of the zone l separating the lower column o already coked and the upper column m of uncoked fuel. p is the closable 25 feed hopper.

The operation of the apparatus is as follows:—

The distilled fuel, the coked fuel, in the lower portion of the furnace, is blown red 30 hot in the generator by the air from the valve α_1 which ascends through this part, descends through the second part of the shaft, leaves the same through valve b_1 and escapes through the chimney d . Now steam 35 is fed into the hotter part of the double shaft from below at c_1 or on both sides at c_1 and c_2 , and the water gas thereby produced meets in the separating zone e , the upper air blown in through the air pipe i , 40 which raises the temperature by a partial combustion in this separating zone, distils the coal in the fuel column as it ascends therethrough and leaves the furnace through the outlet f , the receiver h and the gas-valve g . 45

50 The next blast is done in the opposite direction, inasmuch as the air enters the gen-

erator furnace through the valve α_2 at the bottom of one part of the double shaft, whereas the burnt gas escapes into the chimney at the bottom of the opposite part 55 near b_2 .

For increasing the temperature and the combustion of the unburnt gases still produced from half-cooked fuel in the double shaft, secondary air may be fed through 60 the air valve e during the hot blast and by a sufficient supply of upper air during the blast, a temperature so high may be attained in the separating zone that during the gas-period, a supply of upper air through the valve e becomes superfluous. In case of need, steam may be supplied through the valve n during the gas-period, by which means a higher amount of ammonia can be received.

The principle of the invention permits, of course, many embodiments. The fire-bridge is to be dimensioned in such manner that its crown will lie in the neighborhood of the zone separating the columns of coked and uncoked fuel.

With large furnaces this construction may lead to the formation of two separately lined single shafts.

The process may be executed in a known manner to produce generator-gas or water-gas. As fuel any bituminous fuel, as black coal, brown coal may be used.

What I claim as my invention and desire to secure by Letters Patent is:—

A process of gas generation from a column of solid fuel consisting of a blow period in which the lower portion only of said column is blown with air and a run period alternating therewith in which steam 90 is passed upwardly through the said lower portion, air added to the water gas so formed, and the resulting products passed through the upper portion of the fuel column.

In testimony whereof I affix my signature, in presence of two witnesses.

EUGEN DOLENSKÝ.
